REMOVABLE PAD FOR SPORT SHIRTS AND JACKETS

Charles Solomon, New York, N. Y.

Application October 23, 1944, Serial No. 559,908

1 Claim. (Cl. 2—268)

1

This invention relates to new and useful improvements in a garment.

More specifically, the invention proposes the construction of a garment having removable shoulder pads, the garment being adapted to be worn as a sport jacket when the shoulder pads are attached, and to be worn as a sport shirt when the pads are removed.

Still further it is proposed to provide a garment as aforesaid in which the pads may be removed for cleaning both for sanitary purposes and in order to avoid bunching and hardening of the said sanitary shoulder pads.

Still further it is proposed to provide a garment as aforesaid in which the pads are connected to one end by a hidden "zipper" and at the other end by a snap fastener.

Another object is to provide a garment as aforesaid having a double yoke forming at each shoulder two pockets for two removable pads, the pads being secured in place by snap fasteners or other similar means.

Another object is to provide a garment as aforesaid having a shoulder pad in each shoulder, each pad having its "zipper" along one side and its snap fastener at the peak opposite thereto.

For further comprehension of the invention, and of the objects and advantages thereof, reference will be had to the following description and accompanying drawings, and to the appended claim in which the various novel features of the invention are more particularly set forth.

Fig. 1 is a front view of a garment constructed in accordance with this invention.

Fig. 2 is a plan view of the garment.

Fig. 3 is a fragmentary enlarged view of the garment showing a shoulder pad.

Fig. 4 is a view similar to Fig. 3 with the snap fastener undone and the pad turned over.

Fig. 5 is a side view of the pad, with the adjacent parts of the garment being shown in section.

Fig. 6 is a central section of the pad and adjacent parts of the garment.

Fig. 7 is a section on the line 1—1 of Fig. 3.

Fig. 8 is a view similar to Fig. 1 or a garment constructed in accordance with a modification of this invention.

Fig. 9 is a plan view of the garment of Fig. 8.

Fig. 10 is a fragmentary view of the inside of the garment of Fig. 8 at the shoulder portion thereof.

Fig. 11 is an enlarged fragmentary inside view showing the shoulder pad and associated structure of the garment of Fig. 8.

2

Fig. 12 is an enlarged inverted plan view of the pad of the garment of Fig. 8.

Fig. 13 is an enlarged fragmentary rear view of the shoulder portion of the garment, viewed from the outside thereof.

Fig. 14 is an enlarged section on the line 14—14 of Fig. 13.

Fig. 15 is a similar view to Fig. 2 but illustrating a further modification of the invention.

Fig. 16 is an enlarged fragmentary inside view showing the shoulder pad holding structure of the garment illustrated in Fig. 15.

Fig. 17 is an enlarged inverted plan view of the pad used in the garment illustrated in Fig. 15.

Fig. 18 is a fragmentary view of the inside of the garment shown in Fig. 15, at the shoulder portion thereof.

Fig. 19 is an enlarged transverse sectional view taken on line 19—19 of Fig. 18.

20 The garment according to this invention, may be worn by either man or woman, and comprises a front 10 buttoned down the middle, a collar 11, sleeves 12, pockets 13 and a back 14. In each shoulder on the inside of the garment is sewed a 25 "zipper" strip 15, this strip extending along the seam 16 where the sleeve meets the front and back of the garment. Thus when the garment is worn without the pads, the strip is not noticeable. A snap fastener eye 17 is secured to the seam 18 between the front and back of the garment and between the seam 16 and the collar of the garment.

20 A removable shoulder pad 19, has a snap fastener snap 20 in one peak or corner of the pad, this snap 20 being adapted to coact with eye 17 35 to hold one end of the pad to the garment. A "zipper" strip 21 is sewed across the pad parallel to the base thereof opposite the peak having the snap 20 and slightly spaced from this base, strip 21 coacting with strip 15 to secure the pad at another point to the garment. Strip 21 is provided 40 with a "zipper" control 22 for effecting connection of the two "zipper" strips. The stitches securing a strip 21 to the pad, divide the pad into two portions, a large portion 23 and a small portion 24.

45 When two pads are secured to the garment, the "zipper" is between the pad and the garment so that it is hidden and does not come in contact with the wearer. To remove the shoulder pads, 50 the snap fasteners are first opened and the pads folded over to the position shown in Fig. 4. The "zippers" are then opened and the pads removed. Thus the garment can be quickly changed from a jacket to a shirt, and vice versa.

55 Each of the pads is made of two triangular

sheets of cloth with their edges folded in, and stuffed with cotton or other material. By placing the snap fastener eye in one seam and the "zipper" strip in another seam of the garment, they are not noticeable from the exterior of the garment either when the garment is worn as a shirt or as a jacket.

A garment constructed in accordance with a modification of this invention is shown in Figs. 8-14. It has a front 10', a collar 11', sleeves 12', 10 pockets 13' and a back 14'. The important features of the back are best shown in Fig. 13 where it will be seen that beneath the collar 11' there is a wide strip 25 extending entirely across the back and meeting the tops of the sleeves at the shoulders. Thus this strip 25 rests on the top of a person's shoulders when the garment is worn. The back also has pleats 26.

On the inside of the garment the strip 25 is lined with a lining or strip 27, the strips 25 and 27 being sewed together along their longitudinal edges or seams 28' only to form a double yoke, and being open at their ends providing two pockets 28. The edges of the ends of the strip 27 are protected by tape 29, which is in line with the seam 16' between the sleeve and the body of the garment. A shoulder pad 30 is disposed in each pocket, that is to say, in the space between the strips 25 and 27 at the ends thereof.

Pad 30 is slightly wider at its side 31 disposed in the shoulder of the garment than at its side 32 which is adjacent the collar of the garment. The edges at side 31 are tucked in and sewed together but the edges at side 32 are taped. Side 31 is curved concavely to provide a well fitting shoulder pad. Side 32 is slightly convex but it may be straight if desired. The pad is stuffed with cotton 33. In its longitudinal center, spaced a short distance from the side 31, the pad has a snap fastener snap 34 which divides the pad into a small portion 35 and a large portion 36.

A snap fastener eye 37 is secured to the strip 27 in its longitudinal center at each end thereof partially in the tape 39, the eye opening inwardly into the space between the strips 25 and 27. Each pad is secured in place by means of its snap coacting with the correlated eye. When so disposed the portion 35 of the pad extends outwards beyond the seam 16', forcing the shoulder outwardly to provide a square effect, such effect being desirable when the garment is being worn as a jacket. When the pads are removed, the shoulders of the garment will slouch comfortably over the shoulders of the person wearing the garment so that the garment forms a suitable sport shirt.

While the pads 19 of the garment of Fig. 1 are not shown extending materially outwardly of the seam 16', they may be similar to the pads 30 if desired, and similarly, the pads 30 may be disposed as are the pads 19 if desired.

From the foregoing description of the two embodiments of the present invention, it will be seen that a combination jacket-sport shirt has been provided which can be quickly changed from one to the other without making any alterations

in the garment itself. The garment of Figs. 8-14 has the advantage over the garment of Figs. 1-7 that a pocket is provided for the pads making it unnecessary to secure them other than by the single snap fastener. In other respects the garments have similar advantages.

The feature of removable pads, besides making the garment a combination jacket-sport shirt, also provides for the easy cleaning and replacement of the pads, which is an essential feature in keeping the garment sanitary. The person owning the garment may have several sets of pads of different shapes and thicknesses so that these shoulder pads may be interchanged at will. The pads are of economical construction so that the cost of extra pads is not prohibitive.

While a "zipper" and snap fasteners have been shown and described as preferable means for securing the pads in place, other suitable means such as buttons or hook and eye fasteners may be employed if desired.

In Figs. 15-19, the garment is shown with a front portion 10", a collar 11", sleeves 12", and back 14". In this form of the invention, the shoulder pad 40 may be disposed under a bridging strip 41 and removably secured thereto by snap fastener members 42 and 43. The shoulder pad positioning bridging strip is secured in position by a line of stitches 44 to the seam 16" at one side, and by tacks 45 at the other end of the bridging strip, to the seams 18" of the garment.

In other respects this form of the invention is similar to that previously shown and like reference numerals identify like parts in each of the several views.

This arrangement will also permit ready removal of the shoulder pads when it is desired to wear the garment as a shirt or when the garment is to be laundered.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A shirt or similar garment comprising a front opening down the middle, a back, a collar, two sleeves, a strip connecting said front, back, sleeves and collar, said strip forming the shoulder portions of said garment, a lining for said strip disposed adjacent the under surface thereof and terminating at points adjacent said sleeves, said lining being spaced from said strip except at the longitudinal edges, said longitudinal edges being stitched to said lining thereby forming an opened ended channel, a removable shoulder pad disposed in each end of said channel, each of said pads having a portion thereof extending beyond said strip and into the sleeve portion of said garment, and means releasably securing said pads in said channel.

CHARLES SOLOMON.
